UNITED STATES PATENT OFFICE.

NICHOLAS J. KOEHLER, OF BALTIMORE, MARYLAND.

HAND STAMPING DEVICE.

1,291,026.

Specification of Letters Patent. Patented Jan. 14, 1919.

Application filed August 26, 1918. Serial No. 251,436.

To all whom it may concern:

Be it known that I, NICHOLAS J. KOEHLER, a citizen of the United States, residing at Baltimore, and State of Maryland, have invented certain new and useful Improvements in Hand Stamping Devices, of which the following is a specification.

This invention relates to hand stamping devices and more particularly to that type of devices having a supply of ink, a stamp, and a supporting member whereby the stamp may be conveniently inked and then make its impression upon the paper carried by the supporting member.

One of the objects of the present invention is to provide a simple and practical mechanism of the above general character having relatively few parts which may be conveniently and inexpensively manufactured and assembled. A further object is to provide a device of the above general character particularly adapted for dating checks, and the like, which will permit the stamping members and the supporting member to be conveniently adjusted to suit requirements. A further object is to provide a device of the above general character which may be compactly folded and transported.

Other objects will be in part obvious from the annexed drawings and in part indicated in connection therewith by the following analysis of this invention.

This invention accordingly consists in the features of construction, combination of parts and in the unique relations of the members and in the relative proportioning and disposition thereof, all as more completely outlined herein.

To enable others skilled in the art so fully to comprehend the underlying features thereof that they may embody the same by the numerous modifications in structure and relation contemplated by this invention, drawings depicting a preferred form have been annexed as a part of this disclosure, and in such drawings, like characters of reference denote corresponding parts throughout all the views, in which—

Figure 1 is a perspective view of the device in operative position;

Fig. 2 is a partial sectional end view of the device in folded position;

Fig. 3 is a detail transverse sectional view. For convenience, it will be assumed that 55 the present device is particularly adapted for dating sheets of checks, although it is of course to be understood that it is applicable to various other uses as well.

Referring now to the drawing in detail 60 and more particularly to Fig. 1, 5 represents a base or supporting member of any desired size provided at one side with a straight edge 6 and at one end with a second straight edge 7, both of which are adjustable in a 65 direction transverse to their length by means of set screws 8, thereby to accommodate sheets of different sizes.

At one side of the supporting member 5, is a second member 10, slightly smaller in 70 size, however, and connected to the support 5 by means of slotted links 11 having pivotal connections at 12 with the member 10, and at the point 13 with the member 5. Adjacent the pivot points 13 and at opposite 75 ends of one of the side edges of the support 5 are two upright members 14. The upper end of these uprights pivotally support at 15 laterally extending arms 16. Between the inner ends of these arms is a reinforcing 80 brace 17 while the other ends of these arms are connected by a series of members as shown more clearly in Fig. 3. A main member 18 and a secondary member 20 are spaced apart by a series of rubber blocks 21. At 85 regular intervals are a series of dating stamps 22 secured to the members 18 and 20 by means of bolts 23 provided with tightening or adjusting nuts 24 and an intervening rubber cushion 25, thereby to take up the 90 shock due to operation and to insure a uniform pressure and impression upon the receiving sheet. All of these members are suitably trunnioned at 26, as shown in Fig. 1, whereby the device may turn bodily with 95 respect to the arms 16 which in turn rotate about the pivots 15 on the uprights 14. A suitable manipulating handle 27 is provided as may be necessary for convenience of operation.

Beneath the dating stamps 22 are preferably positioned a plurality of ink pads 28 although of course one single elongated pad may be used, if desired. It is sometimes preferred, however to use a shorter 105 sheet, than that for which the device is de-

signed to accommodate, in which case one of the ink pads may be closed without affecting the operation of the other devices.

In Fig. 2 the device is shown in its compact folded position and concealed within a suitable cover 30 which, of course, is provided with a carrying handle 31 and locking latches 32 adapted to coact with the base-board 5 whereby the entire device may be conveniently transported in a dust-proof manner. A buffer 33 is provided on the inner surface of the casing 30 adapted to coact with the transverse bar 18, thus to prevent rattling and dislocation of the device during transportation.

The device may be conveniently operated as follows:

Assuming it to be in a position shown in Fig. 2, the cover 30 is removed after releasing the latches 32. The auxiliary support 10 is moved to the extreme left, as permitted by the slotted links 11, after which it is swung upwardly over the stamping member and down to the position shown in Fig. 25 1. The various stamping devices are set according to date, for example, or the matter intended to be printed.

The covers of the several ink pads are thrown back and the stamping devices 30 moved into engagement therewith as indicated. The sheet to receive the impressions is placed upon the support 5 and the straight edges moved or adjusted, as may be necessary to properly bring the blanks into position to 35 receive the impressions when the stamping devices are swung over to printing position.

It will thus be seen that the invention contemplates a simple and practical hand stamping device which will be inexpensive 40 to manufacture and assemble, easy and reliable to manipulate and one which may conveniently be transported and adjusted to suit various conditions. In short, the invention is believed to accomplish among 45 others all of the objects and advantages herein set forth.

I realize that considerable variation is possible in the details of construction and arrangement of parts without departing 50 from the spirit of my invention, and I therefore do not intend to limit myself to the specific form shown and described.

I claim:

1. In a device of the character described, 55 in combination, a main support, an auxiliary support having a sliding connection therewith whereby it may be conveniently moved to and from superposed position with relation to the first support, inking pads carried by said auxiliary support, uprights 60 associated with one of said parts and a series of adjustable stamping devices pivotally

supported in said uprights whereby they may be swung from a position adjacent the ink pads to a position above said first support. 65

2. In a device of the character described, in combination, a main support, an auxiliary support having a sliding connection therewith whereby it may be conveniently moved to and from superposed position with 70 relation to the first support, inking pads carried by said auxiliary support, uprights associated with one of said parts and a series of adjustable stamping devices pivotally supported in said uprights whereby 75 they may be swung from a position adjacent the ink pads in a position above said first support, said main support being provided with adjustable straight edges whereby the sheet to receive the impressions may 80 be properly positioned with respect to the impression stamping devices.

3. In a device of the character described, in combination, a main support, an auxiliary support having a flexible connection 85 therewith whereby it may be conveniently moved from a position above said first support to a position at one side thereof, inking pads carried by said auxiliary supports, uprights mounted on the main support, and a 90 plurality of adjustable stamping devices trunnioned in said uprights whereby they may be swung from inking position to impression position, each of said stamps being provided with a cushioning device between 95 the stamp and its supporting member whereby uniformity of impressions may be obtained.

4. In a device of the character described, in combination, a main support, an auxiliary support having a flexible connection therewith whereby it may be conveniently moved from a position above said first support to a position at one side thereof, inking pads carried by said auxiliary supports, uprights mounted on the main support, a plurality of adjustable stamping devices trunnioned in said uprights whereby they may be swung from inking position to impression position, each of said stamps being provided with a cushioning device between the stamp and its supporting member whereby uniformity of impressions may be obtained, said main support being provided with adjustable straight edges at one end and side 100 105 adapted to coact with the impression sheet whereby it may be moved into proper position with respect to the printing devices. 110

In testimony whereof I affix my signature in presence of two witnesses.

NICHOLAS J. KOEHLER.
